UNITED STATES PATENT OFFICE.

GEORGE L. WEBB, OF CRESTWOOD, KENTUCKY.

DESIGN FOR A KITCHEN-RACK.

46,150.

Specification for Design.

Patented July 21, 1914.

Application filed April 30, 1914. Serial No. 835,536. Term of patent 7 years.

To all whom it may concern:

Be it known that I, GEORGE L. WEBB, a citizen of the United States, residing at Crestwood, in the county of Oldham and State of Kentucky, have invented a new, original, and ornamental Design for Kitchen-Racks, of which the following is a specification, reference being had to the accompanying drawing, forming part thereof.

The figure is a perspective view of the kitchen rack, showing my new design.

I claim:—

The ornamental design for a kitchen rack, as shown.

GEORGE L. WEBB.
